PERMANENT BUILT-IN FOLDING BOARDING
LADDER FOR BOATSNorman Robinson, Southport, and Paul R.
Lutters, Fairfield, Conn.

Application June 3, 1950, Serial No. 165,882

6 Claims. (Cl. 114—65)

1

This invention relates to boarding ladders for water craft of various types, and an object is to provide an improved boarding ladder in the form of a folding structure built into the hull of a craft as a permanent part thereof.

In various types of craft, such, for example, as small cruisers and the like, the conventional ladders having outboard steps are unsatisfactorily for many reasons. For example, when a craft is moored to a float or dock the rise and fall of the water causes the projecting ladder steps or other parts to catch on the float or dock with resulting damage.

A further object of this invention is to provide an improved ladder for water craft constructed and arranged so that all parts are always located inboard and have no projecting members which can catch on or be damaged by contact with a float, dock, or other structure.

A further object is to provide a folding ship's ladder capable of use in an emergency, as an escape ladder between decks on larger vessels.

A still further object is to provide a permanent built-in ladder in the side of small craft to take the place of the usual rope ladder frequently used on small cruisers and the like.

With the foregoing and other objects in view, we have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a vertical section through a part of the hull of a craft equipped with a boarding ladder constructed in accordance with one embodiment of this invention, different portions of the section being taken on different planes as will hereafter appear;

Fig. 2 is a section of a detail;

Fig. 3 is an elevation of a part of the structure shown in Fig. 1, illustrating one of the ladder steps in open operative position, and

Fig. 4 is a plan view of the mechanism shown in Fig. 3.

The illustrated embodiment of the invention is shown incorporated in a hull 11 having a deck 12 and a freeboard 13. One or more openings 14 are formed in the freeboard, and if more than one is used they are spaced vertically above one another a distance corresponding to conveniently arranged ladder steps. The number of openings will, of course, vary according to the height of

the freeboard 13, the two openings 14 shown being exemplary of small craft only.

The invention comprises a folding ladder structure arranged inboard and includes a step-forming member 15 pivoted adjacent the bottom edge 16 of each opening 14 on hinge pins 17 extending outwardly on each side of the step 15 and mounted in bearing openings 18 located in inboard side plates 19 extending vertically of the hull 11 on each side of the openings 14. A rear plate 21 is connected to and holds the side plates 19 in position.

The step-forming members 15 are movable into position to close the adjacent openings 14 in the freeboard 13, as indicated in broken lines in Fig. 1, as more fully described hereafter, or into position to open such openings and form inboard ladder steps, as indicated in solid lines. Each step has supporting and guiding lugs 22 which extend outwardly at each inside corner thereof and slidably engage arcuate slots 23 in the side plates 19. In open position the lugs 22 are supported by the lower ends of the slots 23 so that each step 15 is rigidly supported at each corner when in open step-forming position.

Mechanism is provided for opening and closing the step-forming members, preferably simultaneously and from a convenient location near the deck 12. As illustrated, this mechanism includes an operating quadrant plate 24 adjacent each step 15 having its inner corner 25 secured to the associated hinge pin 17 whereby movement of the quadrant causes the connected step-forming member 15 to move in one direction or the other to open or close the associated opening 14. As illustrated, the quadrant 24 is on the opposite side of the side plate 19 from the step member 15 and the hinge pin 17 extends through the side plate, see Fig. 4. A reinforcing guide pin 24a on the upper corner of the quadrant 24 is slidable in an arcuate guide slot 24b in the side plate 19 and forms a rigid connection between the quadrant 24 and step 15. An operating rod 26 extends vertically along the side plates 19 and is pivotally connected to each quadrant 24 by pivot pins 27 or the like. The lower end of the rod 26 is pivoted to a supporting and guiding link 28 hinged to a bracket 29 mounted on the inside of the hull 11, while the upper end of the rod is pivoted to an operating crank 31 by a pivot pin 32 secured to the upper end of the rod 26 and extending through a slot 33 in an enclosing wall 34. Two such walls 34, 35 enclosing the side plates 19 and fitting into grooves 36 in the end plate 21, provide a closure for the

entire ladder assembly which can be made watertight if desired.

As shown in Fig. 1, the operating handle 31 is pivoted to a supporting bracket 37 mounted inboard on the hull a short distance below the deck 12, a small hatch 38 in the deck giving access to the handle. The hatch opening is closed by a cover 39 or the like. When in raised position the handle engages a spring clip 41 supported on the closure plate 34 or other suitable retaining means for holding it in raised position in which the openings 14 in the freeboard are closed. In Fig. 2, the retaining clip is shown as having a yieldable spring finger 42 engaging the handle 31 and yieldably holding it in a notch 43 in a bracket member 44 mounted on the outer face of the closure plate 34.

Each step 15 is of larger dimensions than the associated opening 14 and has a nonslip tread block 45 secured to the face thereof in any suitable manner, as by a waterproof adhesive. A rabbeted edge 47 on each block is engageable with a similarly formed edge 48 on the associated opening 14 to provide a substantially watertight seal when closed. As shown, each block has a nonslip surface 49. A hand grip for use when the step is open to form a ladder is provided by a depression 51 in the face of the block 45 near the outer edge, or by any other means.

In operation, when the handle 31 is raised and secured by the clip 41 or the like, the step-forming members 15 are all in position to close the adjacent openings 14, as indicated in broken lines in Fig. 1, their outer surfaces being flush with and forming a continuation of the outer surface of the hull. When use of the ladder is desired, it is only necessary to lower the handle 31 by pressing it downwardly out of the retaining clip 41 and shift the mechanism into the position shown in the solid lines in the drawing. In this position the step-forming members are each supported in horizontal step-forming position by the lugs 22 engaging the ends of the slot 23. Also, the illustrated quadrants 24 engage the inside wall of the hull and assist in supporting the steps 15.

The invention provides an inboard ladder for small craft, having no projecting steps or other members to catch on and be damaged by floats, docks or the like. On larger vessels the invention can also be employed as an escape ladder between decks for emergency use, as well as a boarding ladder.

The specific embodiment of the invention herein described can be variously modified and adapted within the scope of the appended claims.

Having thus set forth the nature of our invention, we claim:

1. In a water craft having an upright side wall including a freeboard provided with an opening therethrough, a step forming member of a size to fit in and close said opening, supporting means for said member including means to pivotally connect said member at its lower edge to the side wall, said member being swingable inwardly from the opening to a substantially horizontal position behind said wall in substantial alignment with the lower edge of said opening to provide a ladder step, and means to support the member in this position.

2. The combination in a boarding ladder for a water craft having an opening in the side wall of the hull thereof, of a step-forming member of a size to close the opening, hinge mechanism securing said step-forming member adjacent the 75

lower edge of said opening for movement into position to close said opening or into a substantially horizontal position at the inner side of the side wall to provide an inboard step accessible through said opening, means supporting said member in step-forming position including a quadrant plate connected to said member for movement therewith, and having an edge adapted to engage the inner surface of said hull when said member is in step-forming position, and means for moving said member from one position to another.

3. The combination in a boarding ladder for a water craft having an opening in the upright side wall of the hull thereof, of a step-forming member of a size to close said opening, hinge mechanism securing the lower portion of said step-forming member adjacent the lower edge of said opening for movement into position to close said opening or into a substantially horizontal position to the rear of said wall to provide an inboard step accessible through said opening, means supporting said member in step-forming position including a quadrant plate connected to said member for movement therewith, and having an edge adapted to engage the inner surface of said hull when said member is in step-forming position, and means including an operating rod connected to said plate and extending upwardly above said step for moving said member from one position to another.

4. In a boarding ladder for a water craft having an upright side wall provided with an opening in the freeboard thereof, a step-forming member of a size to fit in said opening, pivot means at its lower edge supporting said member for movement into position to close said opening or into a substantially horizontal position at the inner side of said wall to open said opening and form an inboard step accessible through said opening, means supporting said member in step-forming position, including a vertical supporting plate mounted at one side of said opening inboard thereof, a pin on said member extending through an arcuate slot in the adjacent supporting plate so as to engage one end of such slot to support said member when said member is in step-forming position, and means for moving said member from one position to the other.

5. The combination in a boarding ladder for a water craft having an upright side wall and a plurality of vertically spaced openings in the freeboard thereof, of a plurality of step-forming members of a size to close said openings, means supporting one of said members adjacent each opening for movement into position to close said opening or into a substantially horizontal position at the inner side of the side wall to open said opening and form an inboard step accessible through said opening, means supporting each of said members in step-forming position, and means for simultaneously moving said members from one position to the other, including an operating rod connected to each of said members and extending upwardly therefrom, and means accessible for operating said rod including a lever pivotally mounted, and means for retaining said lever in position to cause said members to close said openings.

6. The combination in a water craft having an upright side wall provided with a plurality of vertically spaced openings in the freeboard thereof, of a plurality of step-forming members one for each opening of a size to close the opening, means pivotally supporting said members in-

board of said openings for movement into position to close said openings or into a substantially horizontal position to open said openings and provided inboard ladder steps at the inner side of said wall, means for simultaneously moving said members from one position to the other, a tread block on each step-forming member providing an anti-slip surface, the edge of each tread block being formed to seal the edge of the adjacent opening when said members are in closed position, and a recess on each tread block forming a hand grip when said members are in open ladder-forming position.
